UNITED STATES PATENT OFFICE

LON HERNON, OF CHICAGO, ILLINOIS

BRUSH-COMB

Application filed March 2, 1931. Serial No. 519,435.

The present invention relates to a brush-comb, viz., a unitary device having at one and the same time the combined functions of both a comb and brush.

5 According to the preferred embodiment of the invention, the device is constructed in the general form of a comb having brush bristles mounted in the ends of the comb teeth. Preferably a series of bristles are 10 mounted in the end of each comb tooth, extending across the width of the tooth in a line generally parallel to the line of motion of the tooth through the hair. These bristles only project a comparatively short distance below the ends of the comb teeth. In 15 the preferred construction, the ends of the comb teeth are formed with cavities or recesses therein, elongated in the direction of the width of the tooth, and the bristles extend up into these cavities and are anchored 20 at their upper ends in the top portions of the cavities. By this mounting of the bristles in said cavities only a comparatively short portion of each bristle may be arranged to 25 project beyond the end of the tooth but at the same time each bristle is of sufficient length so that it may flex with sufficient freedom in moving across the scalp to prevent irritation or injury to the scalp. It will be 30 evident that in this type of device the comb teeth function as guards or shields for the bristles, whereby the bristles are primarily active on the scalp rather than on the hair.

One of the principal objects of the invention is to provide a device of this general description which will invigorate the scalp without disturbing the wave in a woman's hair. The frequent and vigorous use of a hair brush is recommended by all hair and 35 scalp authorities as being particularly beneficial to the hair and scalp because the brush bristles invigorate the scalp, effect a distribution of the natural oil over the scalp, remove layers of old scalp, and have a cleansing action ridding the scalp of accumulations of dirt, etc. However, the use of the ordinary hair brush disturbs any artificial wave in the hair, and tends to take the wave out 40 of the hair. With the wide prevalence of Marcel waving and finger waving, women

are refusing to brush their hair, notwithstanding the known benefits of a brush on the scalp. Even with a permanent wave, it is necessary to have the wave set frequently, and the use of the ordinary brush disturbs 55 this setting. As a consequence, women are now experiencing hair and scalp difficulties much more so than when frequent brushing was more prevalent. While it is practically impossible to use the ordinary hair brush without disturbing a Marcel wave or finger 60 wave, yet on the other hand a comb can be used with practically no disturbing effects, and in fact a comb is always used to set the wave. 65

The use of the present brush-comb gives all of the beneficial advantages of brushing but does not disturb the wave in the hair. This follows from the fact that the bristles are almost completely enclosed in the ends of the comb teeth and hence do not catch strands of hair and pull them out of place. The comb teeth enter the hair and part the strands in practically the same way as an ordinary comb, thereby allowing the bristles to reach 70 through the hair and engage the scalp directly, but without permitting the bristles to catch strands of the hair and pull them out of place. 75

Entirely aside from any question of disturbing a wave, another important object of the invention is to provide a device which will have a more direct and beneficial action on the scalp and roots of the hair than the ordinary hair brush. In the use of the ordinary hair brush on a moderately thick head of hair only a comparatively small proportion of the bristles actually reach the scalp, the other bristles moving over the surface of the hair or extending down into the hair but not actually contacting with the scalp. If the bristles are very pliable a smaller proportion will reach the scalp, and if the bristles are made relatively stiff to counteract this the bristles which do reach the scalp will have 85 an irritating action thereon. 90

In the present device the comb teeth part the hair and thereby bring the brush bristles into direct contact with the scalp. Since substantially all of the bristles engage the scalp 100

and roots of the hair their action of invigorating the scalp, distributing the natural oil, and removing layers of old scalp is made more uniform.

Another object of the invention is to provide improved methods of and means for mounting the bristles in the ends of the comb teeth.

Another object is to supplement the bristles in the ends of the comb teeth by additional bristles disposed between the comb teeth, when the latter bristles are desired for brushing the surface of the hair. These additional bristles are confined entirely to the spaces between the comb teeth, the latter then functioning as guards or shields for preventing these bristles from disturbing the wave. In one embodiment these supplementary bristles extend downwardly in the tooth spaces substantially parallel to the comb teeth, but preferably terminating short of the ends of said teeth, and in another embodiment these bristles extend substantially transversely of the teeth.

Another object is to provide a brush-comb having bristles in the ends of the comb teeth, characterized by a particular shaping of the comb teeth whereby they have an improved action in parting or separating the strands of hair.

Another object is to provide a construction permitting ready cleaning of the bristles mounted in the ends of the comb teeth.

Other objects and advantages of the invention will appear from the following description of a preferred embodiment thereof. In the accompanying drawings illustrating this embodiment:

Figure 1 is a side elevational view of one form of brush-comb embodying my invention;

Figure 2 is a transverse sectional view on an enlarged scale, taken approximately on the plane of the line 2—2 of Figure 1 through one of the spaces between the comb teeth which carry bristles;

Figure 3 is a similar sectional view taken approximately through one of these teeth, as indicated by the section plane 3—3 of Figure 1;

Figure 4 is a fragmentary side view on the same enlarged scale as Figures 2 and 3, showing part of the device in longitudinal section and part in elevation;

Figure 5 illustrates a modified method of and means for mounting the bristles in the ends of the teeth;

Figure 6 is a transverse sectional view showing another modified method of mounting the bristles;

Figure 7 is a transverse sectional view and Figure 8 is a longitudinal sectional view on a still larger scale, both illustrating another method of mounting the bristles;

Figure 9 is a fragmentary view similar to

Figure 8 showing a variation of the latter method;

Figure 10 is a fragmentary transverse section showing a construction wherein the lower portion of each tooth is split transversely for mounting the bristles;

Figures 11 and 12 illustrate in longitudinal section two steps of mounting the bristles by forcing bristle containing clips up into the ends of the comb teeth;

Figures 13 and 14 are transverse sectional views illustrating in assembled and disassembled relation a modified construction wherein the device is split longitudinally into separate halves;

Figure 15 is a horizontal sectional view taken approximately on the plane of the line 15—15 of Figure 13.

Figure 16 is a transverse sectional view of a modified construction and Figure 17 is a horizontal sectional view on the line 17—17 thereof; and

Figure 18 is an elevational view of a cleaning brush for the brush-comb.

Referring to Figures 1—4, the device is preferably constructed along the general lines and form of a conventional comb, comprising a back 20 from which extends a row of comb teeth 21. The bristles projecting from the ends of the comb teeth are indicated at 22. If desired, the entire length of the comb may be devoted to the teeth 21 carrying the bristles 22, or, as shown in Figure 1, one end of the comb may have these teeth and the other end of the comb may have conventional comb teeth 23, which may be either coarse or fine. The bristle bearing teeth 21 may also be either coarse or fine, and of any desired length. The body of the device including the back 20 and teeth 21 and 23 may be composed of any suitable material, such as rubber, micarta, bakelite, vulcanite or metal. The ends may be provided with the conventional end bars 24 for protecting the comb teeth.

Referring to Figures 2 and 3, when it is desired to have each tooth carry a considerable number of bristles the lower end of the tooth can be made slightly wider than the ordinary comb tooth. However, when using a smaller number of bristles each tooth can be made comparatively narrow, approximating the width of a conventional comb tooth. Preferably the side edges of the teeth curve inwardly, as indicated at 25, and then flare outwardly to form the sloping lower edges 26, such being desirable in the wider widths of comb teeth. The sloped edges 26 are advantageous for parting the strands of hair and deflecting them upwardly so that they pass between the comb teeth instead of being pressed down under the ends of the teeth. The ends of the teeth may be cut straight across, or might have a convex curvature, although in the preferred form I form these ends with a concave curvature, as indicated at 27, which

enables each tooth to conform more closely to the shape of the head in moving through the hair, thereby reducing the possibility of any appreciable amount of the hair becoming 5 caught or ensnared with the bristles 22.

The bristles are preferably set in a cavity 28 formed in the lower end of each bristle bearing tooth. As previously remarked, the advantage of this is that even with only a 10 comparatively short length of bristle extending beyond the end of the tooth the bristles still have sufficient flexing length so that in moving over the scalp they can flex freely to avoid irritating the scalp and to prevent 15 breaking or permanent bending of the bristles. While this is the preferred arrangement it will be understood that the invention broadly contemplates the mounting of the bristles in the solid end of a comb tooth with 20 no cavity provided for giving a greater flexing length to the bristles. Where the cavities 28 are employed they may be cored out in the molding of the device or they may be cut in the ends of the teeth by a suitable gang 25 arrangement of cutting devices.

In Figure 3 I have illustrated the upper ends of the bristles as being set in a material 31. This may represent a rubber cement or any suitable adhesive poured or inserted 30 into the ends of the cavities 28; or, it may represent a clip or insert composed of rubber or any other suitable material in which the bristles are first anchored, this clip being then inserted up into the end of the cavity 35 and being cemented or vulcanized in the tooth.

If it is desired to have a brushing action effective on the strands of hair as they pass between the comb teeth 21 I may provide 40 supplementary bristles 33 mounted in the spaces between the comb teeth, as shown in Figures 2 and 4. The latter bristles, which are preferably more pliable than the bristles 22, are arranged in bunches and are anchored 45 to the back bar 20 of the device. I have shown the bristles as entering the tapered sockets 34 in the back 20, such being preferred when it is desired that the bristles have a pronounced side flare at their lower 50 ends, and the bristles may be anchored in these sockets by a wire 35 threading therethrough, or the bristles may be cemented in place. When the bristles are wired in place a groove 36 is provided along the back edge 55 of the bar portion 20 for receiving such wire, this groove being afterwards closed over by a filling or insert vulcanized in the groove. The bristles 33 preferably terminate short 60 of the lower ends of the comb teeth 21, and because these bristles are closely confined on each side by the teeth and do not project beyond the front and rear edges of the teeth 65 they do not disturb the wave in the hair, the comb teeth functioning as guides or 70 shields for these bristles so that they merely

brush the hair without tending to pull it out of place.

Figure 5 illustrates a method of mounting the bristles in the ends of the comb teeth. In this method the bristles are inserted into the cavities 28, and vulcanizing jaws or clamps 38 are then engaged over the outer sides of the comb teeth, these members being heated and subjected to pressure, whereby 75 they close the sides of the cavities together at the upper end thereof, and vulcanize these sides together over the bristles. The side walls 21 of each tooth on the outer side of the cavity 28 will generally be sufficiently 80 flexible to permit these walls being pressed together for vulcanizing over the upper ends of the bristles; although, if it is desired to have additional flexibility, each tooth may be slotted completely through from one edge to the other up to substantially the upper end 85 of the cavity, as indicated by the slot 39 in Figure 10, in which case after the bristles have been vulcanized between the compressed upper portions of the cavity the outer edges of the slot are closed by vulcanizing 90 together down along the sloping edges 26. The sets of teeth may be treated alternately to afford sufficient room between the teeth for the members 38. If desired, a filling of vulcanizing rubber 41 may be disposed in the upper end of each cavity. During 95 the operation of securing the bristles in place the bristles may be held in a suitable clamp or mounting jig 42 so as to maintain the bristles in their proper spaced relation 100 until they are securely anchored. The lower ends of the bristles may then be cut to have the proper length projecting from the lower ends of the comb teeth. As previously remarked, only comparatively short lengths 105 of the bristles project beyond the teeth. The lower portion of the cavity 28 in each tooth is made just a trifle wider than the thickness of the bristles so that the bristles can flex 110 freely in the cavity.

In Figure 6 I have shown the bristles as being preliminarily mounted in a mounting clip 45 which is then inserted up into the cavity and is suitably secured therein. As 115 illustrative of one method of securing the clip, a wire 35' may be passed through an aperture in the clip or otherwise secured thereto, this wire passing through a bore 46 in the tooth and being used to pull the clip 120 up into place. The wire securing means 35' for all of the clips 45 may then be anchored in the groove 36 extending along the top of the back bar 20, and where the supplementary bristles 33 are employed this wire securing means may constitute a part of the same securing means which fastens these supplementary bristles in place.

Figures 7, 8 and 9 illustrate other methods of mounting the bristles by the use of clips. According to the arrangement illus-

trated in Figure 8, the comb teeth are provided with transverse openings 28a somewhat similar to the recesses or cavities 28, but extending entirely through the tooth. The lower ends of these openings are defined by the solid bar portions 48 extending across the bottom of the tooth, one on each side of the slotted opening 28b through which the bristles extend. In this form the bristles are mounted in clips 49 composed of rubber or the like, which clips are of substantially the same thickness as the comb teeth. As shown at the left in Figure 8 these clips, with the bristles mounted therein, are passed up into the spaces between the comb teeth and are then moved downwardly to insert the bristles down through the slot 28b, the clip then being moved sidewise into the upper end of the opening 28a. Thereupon the clips are secured in the upper ends of said openings by cementing or vulcanizing the same around the upper and side peripheral edges 49' of the clip. The lower transverse edge of the clip terminates short of the bottom cross bars 48 of the tooth, thereby leaving openings 51 in the comb teeth extending entirely through each tooth so as to enable access to be had to the upper portions of the bristles for washing and cleaning the same with a brush or the like.

Figure 9 illustrates a construction and method of mounting the bristles which is generally similar to the arrangement illustrated in Figure 8, with the exception that the upper portion of the transverse opening does not extend entirely through the tooth, and the clip 49a is only made sufficiently thick to fit in this opening. That is to say, the upper portion of the opening, designated 28c, is merely a recess in the side of the tooth, and the clip 49a carrying the bristles is made of just sufficient thickness to fill in this recess, being then cemented or vulcanized in place. In such arrangement, the lower cleaning opening 51 may be provided on only one side of the tooth, or may extend entirely therethrough. If desired, the side edges of the teeth may also be provided with slots 52 coextensive with the side openings 51, as shown in Figure 7, to facilitate cleaning the teeth bristles from the edges of the teeth. These cleaning openings 51 or 52 or both may be embodied in any of the forms herein disclosed. Also, these edge slots 52 may be made of sufficient height to permit the bristle carrying clip to be pushed into the tooth from its edge through one of these slots.

The invention contemplates the provision of short bristles extending transversely into the space between the comb teeth. For example, the clips 49 and 49a of Figures 8 and 9 may have a multitude of bristles imbedded therein with the ends of the bristles projecting laterally from the side face of the clip, as indicated at 53. The projecting ends of

these bristles are made comparatively short so that they will not extend across the entire width of the space between the comb teeth, and they are preferably relatively pliable so that the hair may readily pass up between these transverse bristles. It will be evident that these bristles will engage above and below the strands of hair for thoroughly brushing and cleaning the latter. If desired, these lateral or transverse supplementary bristles 53 may be arranged up along the entire side wall of the tooth, on one or both sides thereof, up to approximately the back bar portion 20, by either making the mounting clip of appropriate length or by suitably securing said bristles in the body portion of each comb tooth above said clip. These transverse supplementary bristles 53 may be embodied in any of the other forms described herein. In mounting the transverse bristles 53 in the clips or in the body portion of the tooth, their anchorage may be made more secure by forming a sharp kink or right angle bend in the end of the bristle and then embedding this bent end in the clip or tooth, and this same practice may also be followed in mounting the tooth bristles 22 in the clips, or when vulcanizing or cementing these latter bristles in the comb teeth.

Figures 10 and 11 illustrate a modified arrangement and method wherein the bristle bearing clip 55 is forced up into the comb tooth from the lower end thereof and is caused to lock in place in a transverse opening 56 in the tooth. The lower edge of said opening forms shoulders 57 for locking the clip against displacement. Where the comb teeth are sufficiently flexible the sides of the cavity 28 may be sprung apart sufficiently to enable the clip 55 to be forced through the cavity up into the transverse opening 56. As an alternative measure, the tooth may be slit transversely from side to side, as indicated at 39 in Figure 10, so as to enable the side walls of the tooth to separate more readily when the clip is being pushed up into place, and thereafter the edges of the tooth may be vulcanized or otherwise secured together along the edges of the slit. When the clip is in place the engagement of the bottom shoulder thereof with the shoulder 57 of the transverse opening anchors the clip against displacement. In Figure 12 I have illustrated in dotted lines how such a clip may be first placed between the teeth and then moved downwardly to insert its bristles down through the cavity 28, the clip being finally snapped sidewise into the transverse opening 56. The latter method does not necessitate any spreading or slitting of the lower ends of the teeth.

In Figures 13-17 I have illustrated constructions wherein the device is made up of two longitudinally split halves which are joined together to complete the unit. In

each of these two constructions, the back bar 20 is split into two longitudinally extending sections 20a and 20b extending throughout the length of the device, or through that length carrying the brush-comb teeth. In the construction shown in Figures 13-15, each brush-comb tooth 21 is split transversely, or at right angles to the line along which the back bar portions 20a and 20b are split, and one of these back bar portions carries one of the split sections of all of the teeth and the other back bar portion carries the other companion sections of the teeth. That is to say, the bar section 20a carries all of the tooth sections 21a, forming one side of each tooth, and the bar section 20b carries all of the companion tooth sections 21b which form the other sides of all of the teeth. The upper edges of the projecting tooth sections are cut square, as indicated at 61, to engage under the opposite back bar portion. The device is assembled by bringing the companion tooth sections 21a and 21b into proper matching relation and then sliding them together to bring the two upper bar sections together at their meeting line. These upper bar sections may then be secured together in any suitable manner such as by vulcanizing, welding or pinning, depending upon the material employed. Where the device is composed of rubber, the tooth sections of all of the teeth are then vulcanized together along their vertical edges 25, 26, or where the device is composed of metal these edges may be welded together, or might be lapped. Figure 15 illustrates one of the teeth in transverse section, from which it will be seen that a slight space is left between the lower portions of the companion sections of each tooth for accommodating the tooth bristles 22. These bristles may be secured directly to one of the sections of each tooth, or a mounting clip carrying the bristles may be secured thereto, before the tooth sections are assembled, such affording an easy method of mounting the bristles. The aforesaid space between the lower portions of the tooth sections affords the cavity 28 in the lower end of each tooth, which permits the bristles to flex in their movement over the scalp.

In Figures 16 and 17 I have illustrated a construction wherein both the back bar portion and all of the bristle carrying teeth are split on a longitudinal dividing line. One-half of the bristle cavity 28 is formed in the left-hand tooth section 21c, and the other half of the cavity is formed in the right-hand tooth section 21d. Where a clip mounting of the bristles is to be utilized, the upper portion of each cavity or recess may be cut back at an angle, as indicated at 64, to form a wedge shaped socket in the upper end of the cavity. The mounting clip 65 would then be formed with correspondingly sloping side walls adapted to engage with the sloping

edges 64 of the socket. In assembling the device the matching sections of each tooth would be brought together over one of these clips 65 whereby the clip would be rigidly held in the wedge shaped socket against downward displacement from the cavity. The upper back bar portions 20c and 20d would be secured together in the same general manner described above, and, if desired, the meeting lines between the tooth sections 21c and 21d might also be secured together or closed.

In any of these latter forms the supplementary bristles 33 or 53 may be incorporated in the construction if desired; and, likewise, the cleaning openings 51 or 52 may be embodied therein.

Figure 18 illustrates a simple and efficient form of cleaning brush which may be provided for cleaning the device. It comprises a frame built up of side members 67 and end members 68. Extending between the side members are a series of twisted wires 69 having bristles 71 fastened between the pairs of twisted wires, the spacing between these twisted wire bristles corresponding to the spacing between the bristle bearing teeth of the brush-comb. By moving these twisted wire cleaning bristles across the lower ends of the comb teeth and up into the cavities in the teeth and into the spaces between the teeth the entire brush-comb can be quickly and easily cleaned. Another provision for cleaning the device may be effected by mounting the tooth bristles in mounting clips, such as I have above described, and arranging these clips in the comb teeth so that they can be removed therefrom for the purpose of cleaning the bristles and also cleaning out the cavities 28.

The tooth bristles 22 have a minimum degree of contact with the main body of the hair and hence, although these bristles uniformly distribute the natural oil over the scalp they do not convey this oil to the main body of the hair. Thus, the present device avoids one of the objections commonly raised to brushing, viz., that of making the hair oily or greasy. Preferably these tooth bristles are arranged in a single row in each comb tooth so that the teeth may be made comparatively narrow, but they might be grouped in several rows or may be arranged in tufts.

While I have shown what I regard to be the preferred embodiment of my invention and the preferred manner of making the same, nevertheless it will be understood that such are merely exemplary, and that numerous modifications and rearrangements may be made therein without departing from the broad spirit and scope of my invention.

I claim:

1. A brush-comb comprising comb teeth, and brush bristles anchored in and projecting from said comb teeth.

2. A brush-comb comprising comb teeth, and brush bristles projecting from the ends of said teeth. 15. A brush-comb comprising a back bar portion, comb teeth extending therefrom, bristles mounted in the lower ends of said comb teeth, and means securing said bristles in said teeth extending up into said back bar portion. 70
3. A brush-comb comprising comb teeth, and a row of bristles anchored in the lower end of each tooth extending substantially in a line in the direction of the width of the tooth. 16. A brush-comb comprising comb teeth, clips having bristles extending therefrom, one of said clips being mounted in each of said comb teeth with the bristles projecting 75 from the teeth, and cooperating shoulders on the clips and on the comb teeth for holding said clips in place. 80
4. A brush-comb comprising comb teeth having recesses in the ends thereof, and brush bristles in said recesses. 5. A brush-comb comprising comb teeth having recesses therein elongated in the direction of the width of the teeth, and bristles secured in said recesses and projecting from the ends of the teeth. 17. A brush-comb comprising a back bar portion divided longitudinally into two sections, comb teeth each divided into two sections one of which is carried by one back bar section and the other by the other back bar section, said back bar sections being joined together with the tooth sections in assembled 85 relation, and brush bristles carried by the comb teeth. 85
6. A brush-comb comprising a plurality of comb teeth, each of said comb teeth having a cavity in the lower end thereof elongated in the direction of the width of the tooth, and a plurality of bristles mounted in each cavity in a row extending in the elongated dimension of the cavity, each cavity permitting the bristles therein to flex laterally as the projecting 25 ends of the bristles pass over the hair or scalp. 90
7. A brush-comb comprising comb teeth, brush bristles projecting from the ends of said comb teeth, and supplementary bristles extending into the spaces between the comb teeth. 95
8. A brush-comb comprising comb teeth, brush bristles projecting from the ends of the comb teeth, and supplementary bristles extending downwardly in the spaces between the comb teeth. 100
9. A brush-comb comprising comb teeth, brush bristles projecting from the ends of the comb teeth, and supplementary bristles projecting substantially transversely into the spaces between the comb teeth. 105
10. A brush-comb comprising comb teeth, and bristles anchored in the teeth and projecting laterally into the spaces between the teeth. 110
11. A brush-comb comprising comb teeth having cavities in the ends thereof, bristles adapted to project from the ends of said teeth, and means in the upper ends of said cavities mounting said bristles therein to have their ends project beyond the ends of the comb teeth. 115
12. A brush-comb comprising comb teeth, clips carried by said comb teeth, and bristles extending from said clips. 13. A brush-comb comprising comb teeth, and brush bristles extending from said teeth, said teeth having openings therein above their lower ends, for cleaning said bristles. 120
14. A brush-comb comprising comb teeth having slotted openings in their lower ends and having recesses thereabove open at one side of each tooth, clips mounted in said recesses, and bristles carried by said clips extending down through said slotted openings. 125
